Des. 221,564
Patented Aug. 24, 1971

221,564

TOY BACKHOE BODY

Lee J. Pfeilsticker, Mound, Minn., assignor to
Tonka Corporation, Mound, Minn.

Filed July 27, 1970, Ser. No. 24,127

Term of patent 7 years

Int. Cl. D21—01

U.S. Cl. D34—15

FIG. 1

FIG. 2

FIG. 3

FIG. 4

FIG. 5

FIG. 6

FIG. 7

FIG. 1 is a front, right side and top perspective view of the toy backhoe body showing my new design; and FIG. 2 is a rear, left side and top perspective view thereof; and

FIG. 3 is a left side elevational view thereof; and FIG. 4 is a top plan view thereof; and

FIG. 5 is a right side elevational view thereof; and FIG. 6 is a front elevational view thereof; and FIG. 7 is a rear elevational view thereof.

I claim:

The ornamental design for a toy backhoe body, as shown.
